Primary Examiner — Clare E Heflin(74) Attorney, Agent, or Firm — Li & Cai Intellectual Property (USA) Office(57) CLAIM

The ornamental design for a “light fixture,” as shown and described.

DESCRIPTION

FIG. 1 is a perspective view of a light fixture showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view from another visual angle thereof;

FIG. 9 is a perspective view showing my design duplicated only to demonstrate how it would appear in use; and,

FIG. 10 is a sectional view taken along the line X-X in FIG. 9.

The broken line showing of the environment is for illustrative purposes only and forms no part of the claimed design.

1 Claim, 7 Drawing Sheets(56)
